HEAT EXCHANGER

Perry R. Cassidy, Short Hills, N. J., assignor to
 The Babcock & Wilcox Company, Newark,
 N. J., a corporation of New Jersey

Application August 3, 1935, Serial No. 34,506
 Renewed April 15, 1937

22 Claims. (CL 122—355)

My present invention relates in general to the construction and operation of heat exchangers, and more particularly, to heat exchangers especially adapted for the recovery of heat from corrosive, or potentially corrosive, gases, while under a pressure above atmospheric.

The main object of my invention is the provision of a tubular heat exchanger of the character specified which is further characterized by a higher operating efficiency, greater heat absorbing capacity per foot of space occupied, less maintenance cost, and greater ease of access for inspection, cleaning and replacement of the tubes than heat exchangers heretofore employed in this service.

In tubular heat exchangers used for the recovery of heat from corrosive or potentially corrosive gases, such as gases containing sulphur dioxide, the gases readily combine with any moisture present on the tubes due to small leaks or from the sweating that ordinarily occurs at the tube joints, causing local corrosion at these points. This condition necessitates frequent inspection, cleaning and replacement of the tubes and connections, with a relatively high loss of operation of the apparatus. Corrosion also occurs due to condensation of water vapor in the heating gases on the tubes and its combination with the corrosive constituent or constituents of the gases.

In accordance with my invention an unusually high operating efficiency is maintained in such heat exchangers by the provision of a gas-tight casing for the gases, reduction of external heat losses, effective arrangement of the heat absorbing surface, low pressure drop through the apparatus, and low cost of maintenance of the apparatus. A particularly low cost of maintenance is possible as all of the tube joints are located in zones free from corrosive gases so that any leakage occurring at the joints is of minor consequence, the joints may be conveniently examined without interrupting the operation, the tubes may be cleaned throughout their length with a standard turbine cleaner, and tube repairs and replacements may be readily effected by removing an entire section of the heating surface and casing as an integral unit. Tube replacements are greatly reduced by an adequate circulation of the heat absorbing fluid throughout the heating surface. Provisions are also made for short-circuiting the heating gases about the heating surface to facilitate starting of the associated fuel burning apparatus and to maintain the outlet temperature of the heating gases

from the heat exchanger above the condensation point of the water vapor included therein.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

My invention is specifically illustrated as embodied in a steam generating unit for cooling and recovering heat from corrosive gases under pressure and mainly consisting of sulphur dioxide; and in the drawings:

Fig. 1 is a longitudinal vertical section taken on the line 1—1 of Fig. 2;

Fig. 2 is a transverse vertical section taken on the line 2—2 of Fig. 1;

Fig. 3 is a front view of the unit;

Fig. 4 is a horizontal section taken on the line 4—4 of Fig. 2;

Fig. 5 is a horizontal section taken on the line 5—5 of Fig. 3;

Figs. 6 and 7 are side and transverse sectional views respectively of the tube supporting arrangement;

Fig. 8 is a transverse vertical section taken on the line 8—8 of Fig. 1;

Fig. 9 is a horizontal section taken on the line 9—9 of Fig. 8;

Fig. 10 is a horizontal section taken on the line 10—10 of Fig. 8;

Fig. 11 is an enlarged view of one of the walls shown in Fig. 1;

Fig. 12 is a vertical section taken on the inner side of the wall illustrated in Fig. 11;

Fig. 13 is a horizontal section taken on the line 13—13 of Fig. 1;

Fig. 14 is a vertical section taken on the line 14—14 of Fig. 13; and

Fig. 15 an enlarged view of a portion of Fig. 5.

In the embodiment of the invention illustrated in the drawings a gas-tight casing is formed by a vertical front wall 1, a rear wall 2, opposite side walls 3 and 4, a floor 5, and arched roof 6, collectively defining a casing substantially rectangular in horizontal and vertical cross-section. The side wall 3 is provided adjacent its lower end with a corrosive gas inlet 7, while the opposite side wall 4 has a gas outlet 8 of smaller diameter than and concentric with the gas inlet 7. The interior of the casing is divided into a

50

45

55

55

pair of vertical upflow and downflow serially connected gas passes 9 and 10 respectively by a longitudinally extending fire brick baffle 11 extending upwardly from the floor 5 and terminating short of the roof 6. By this arrangement the hot gases entering the inlet 7 will pass upwardly through the gas pass 9, over the upper end of the baffle 11, downwardly through the gas pass 10, and exit through the gas outlet 8.

10 The heat absorbing surface of the unit comprises a vertical series of horizontal rows of single return bend or U-tubes 12 and 13 extending longitudinally of each of the gas passes from opposite end walls of the casing. The tubes 12 have oppositely inclined vertically aligned leg portions extending through the front wall 1, while the tubes 13 have oppositely inclined leg portions extending through the rear wall 2. As shown in Figs. 1 and 2, each of the tubes 12 has its leg portions arranged substantially parallel to and staggered relative to the correspondingly inclined leg portions of the tubes 13 in the vertically adjacent rows, and its return bend or loop portion adjacent to the opposite side of the gas pass and extending transversely of the adjacent leg portions of corresponding tubes 13 in vertically adjacent rows, and vice versa. Three U-tubes 12 or 13 are shown in each horizontal row so that, as shown in Fig. 2, there will be vertically spaced groups of six staggered tube legs in each gas pass of the heat recovery zone. The tubes may be of corrodible steel. Groups of header boxes 14 are arranged externally of the gas passes for serially connecting the adjacent leg portions of corresponding tubes 12 in vertically adjacent rows. Corresponding header boxes 15 serially connect corresponding tubes 13 in a similar manner. Two sets of parallel flow fluid circuits are thus provided for each gas pass with all connecting joints external thereof.

40 When the tubes 12 and 13 constitute the heat absorbing surface of a steam boiler, a steam and water drum 16 is symmetrically arranged longitudinally of and supported on the roof of the casing. A positive fluid circulation is maintained between the drum 16 and the tubes 12 and 13 by means of pairs of downcomer tubes 17 and 18 respectively extending from the bottom of the drum 16 to pairs of headers 19 and 20 respectively. Each header 19 is connected to the lowermost legs of the tubes 12 in one gas pass, while each header 20 is connected to the lowermost legs of the tubes 13 in one gas pass. The uppermost legs of the tubes 12 are connected to separate header boxes 21 having separate detachably connected risers 22 leading to the drum 16. The uppermost legs of the tubes 13 are similarly connected through boxes 23 and risers 24 to the drum 16. The header boxes 14, 15, 21, and 23, and headers 19 and 20 are provided with the usual hand hole connections for expanding and cleaning the tubes connected thereto. The drum 16 is provided with the usual steam outlet, gage, and safety valve connections. The described location of the drum 16 provides a relatively high head and with the inclination of the tube legs insures a rapid fluid circulation through all parts of the heat absorbing surface, thus minimizing overheating and burning out of the tubes 12 and 13.

75 The drum 16 is provided with a pair of spaced internal baffles 26, one at each end of the drum, extending longitudinally of and across the bottom of the drum. The baffles are closed at one end by plates 28 to provide a pair of similar com-

partments 27 open at their ends adjacent the middle of the drum. A feed water supply connection 29 opens to each compartment, and the downcomers 17 and 18 also open into the compartments adjacent their closed ends. The risers 5 22 and 24 however, are connected to the drum 16 above the compartments. This internal drum construction aids in maintaining a positive circulation through the tubes 12 and 13. A blow-off connection is provided for the headers 19 and 10 20 and comprises angle valves 29, pipe 30, a T 31, and valve 32, at each end of the unit, as shown in Figs. 1 and 3.

The specific construction of the casing will now be described. Each of the side walls 3 and 15 4 is formed by a welded sectional metallic cover 33 to which is welded spaced rows of T's 34 for anchoring a thick wall of insulating fire brick 35 in position. A layer of mill board 36 is provided between the refractory and metallic cover, 20 as shown in Figs. 13 and 14.

The construction of the front and rear walls is specifically illustrated in Figs. 1, 3, and 8-15. Each of these walls has a lower section 40 below the tubes 12 and 13 constructed similarly to the 25 side wall construction shown in Figs. 13 and 14, and an upper section 41 of less thickness forming a gas-tight closure for the front and rear sides of the gas passes and having an outer casing 42 for enclosing the pressure parts externally of the 30 gas passes. Each upper wall section 41 has a steel framework 43 fitting around the front and rear sides of the corresponding gas passes and in gas-tight contact with the ends of the side 35 walls 3 and 4 and baffle 11, (see Fig. 15) and removable panels 44 fitting into and closing the corresponding sides of the gas passes. As shown, each panel 44 consists of a metallic tube sheet 45 which is detachably connected to the framework by clamps 46 and covered at its inner side by 40 mill board 47. The tube sheet carries spaced sections of insulating brick 48 between the areas through which the tubes project. The tubes are supported on the panel by having their leg portions expanded into the tube sheet and filling 45 the sections between the brick 48 with plastic refractory 49. The construction described provides a gas-tight enclosure capable of withstanding gas pressures up to 10 lb. per sq. in. without leakage, while minimizing external heat losses. 50 The location of all of the tube joints in an area free from the heating gases avoids corrosion at these points which would otherwise occur due to presence of moisture from small leaks and sweating at the tube joints, which ordinarily combine 55 with the gases and cause local corrosion.

The outer paneled casing 42 which extends over each wall portion 41 is made up by a metallic framework 50 (Fig. 3) which extends outwardly beyond the pressure parts and has its front closed 60 by upper and lower panel sections 51 and 52 respectively, as shown in Figs. 1 and 3, normally held in position by clamps 53 and removable to permit inspection, cleaning and replacement of the tubes. By this arrangement all of the tubes 65 12 or 13 in one gas pass can be removed as a unit by simply removing the panels 51 and 52, disconnecting the riser and downcomer connections, and unbolting the clamps 46 holding the corresponding tube sheet in position. 70

The panels 44 thus provide a cantilever support for the corresponding tubes 12 and 13. The inclination of the tube legs also strengthens the U-tubes. Each of the tubes is thus free to expand and contract at its return bend end during 75

operation. As shown in Figs. 1, 6, 7, and 15, the looped ends of the tubes 12 are prevented from sagging and the tubes held in their desired positions relative to the adjacent tubes by welding 5 a stud 60 to the side of each loop portion in position to extend laterally and rest on the leg portion of one of the adjacent tubes 13 adjacent the wall 2. The loop ends of the tubes 13 are similarly supported adjacent the wall 1. An ex- 10 pansible and contractable supporting engagement is thus provided between the loop end of each tube and a laterally adjacent leg portion of a tube having a cantilever support from the opposite wall.

15 With the foregoing arrangement corrosive gases entering through the inlet 7 pass serially through the narrow gas passes 9 and 10 across the tubes 12 and 13 therein, which being closely spaced provide a high heat transfer rate by con- 20vection. The relatively wide spacing of the tube leg groups permits thick gas layers between the groups and a high rate of heat transfer by gas radiation. While the pressure drop through the unit is relatively low due to the presence of only 25 one baffle therein, it may be desirable under certain circumstances, such as to facilitate starting of the unit or particularly, to regulate the passage of the gases through the unit so that the gas outlet temperature will be sufficiently high to prevent 30 condensation of moisture in the gases and consequent formation of corrosive acids, to by-pass all or a portion of the gases around the heat recovery zone. For this purpose controllable by-pass openings 65 are provided through the baffle 11 below the heating surface to permit the gases to short-circuit the heating surface, as shown in Figs. 2 and 4. The rectangular openings 65 are spaced along the bottom of the baffle 11 and each is provided with a damper tile 66 at its outlet 35 side and mechanism for moving the tile to open and close the by-pass opening. The lower end of each damper tile is rounded and fits into a recessed block 67 in the bottom of the downflow passage 10. Pairs of blocks 68 along the bottom 40 of the side wall 4 serve as supports for each damper tile in its tilted position. The mechanism for independently operating each damper tile consists of links 70 and 71 respectively connected to the damper tile and to an operating 45 shaft 72 journaled in a gas-tight housing 73 below the level of the gas outlet 8. The shaft 72 is actuated by a hand lever 74 as indicated. By these means the amount of gas passing through the heat recovery zone may be controlled to maintain 50 the gas outlet temperature above the condensation temperature of the contained water vapor.

While in accordance with the provisions of the statutes I have illustrated and described herein the best form of my invention now known to me, those skilled in the art will understand that changes may be made in the form of the apparatus and method of operation disclosed without departing from the spirit of the invention cov- 55 ered by my claims, and that certain features of my invention may sometimes be used to advantage without a corresponding use of other features. In the specification and claims the word "corrosive" is intended to generically cover both 60 corrosive gas per se and potentially corrosive gases which form corrosive compounds when combined with liquids.

I claim:

1. A heat exchanger comprising a casing com- 70 prising return bend tubes extending horizontally

in said casing from opposite ends thereof, each of said tubes having a return bend portion extending transversely of vertically adjacent leg portions of vertically adjacent tubes extending from the opposite end of the casing, and means pro- 5 viding a support for said return bend portion from one of said transversely extending leg portions.

2. A heat exchanger comprising a casing in- 10 cluding return bend tubes extending horizontally in said casing and cantilever supported from opposite ends thereof, each of said tubes having a return bend portion extending transversely of horizontally extending oppositely inclined leg portions of vertically adjacent tubes supported at 15 the opposite end of the casing, and means pro- viding a support for each of said return bend portions from one of said adjacent leg portions.

3. A heat exchanger comprising a casing in- 20 cluding vertically spaced rows of single return bend tubes, said tubes extending horizontally in said casing and being cantilever supported from opposite ends thereof, each of said tubes having a return bend portion extending transversely of laterally adjacent leg portions of tubes supported 25 at the opposite end of the casing, and means providing a support for each of said return bend portions from one of said laterally adjacent leg portions.

4. A heat exchanger comprising a casing, heat 30 transfer surface comprising horizontal rows of return bend tubes, said tubes extending in vertical planes transversely of said casing from opposite ends thereof, and each of said tubes having a return bend portion extending transversely 35 of and across the adjacent leg portions of vertically adjacent tubes in superposed rows extending from the opposite end of the casing.

5. A heat exchanger comprising a casing, heat 40 transfer surface comprising vertically spaced horizontal rows of single return bend tubes, said tubes extending in vertical planes transversely of said casing from opposite ends thereof, each of said tubes having oppositely inclined leg portions ex- 45 tends between and staggered relative to the leg portions of adjacent return bend tubes extending from the opposite end of said casing, and each of said tubes having its return bend portion adjacent to said opposite end of the casing and ex- 50 tends transversely of the adjacent leg portions of vertically adjacent tubes in rows extending from the opposite end of the casing.

6. A heat exchanger comprising a casing, heat 55 transfer surface comprising horizontal rows of return bend tubes, said tubes extending trans- versely of said casing from opposite ends thereof, said casing having a tube sheet at each end thereof, each of said tubes having leg portions extending through and expanded into the cor- 60 responding tube sheet and arranged in a plane between the planes of return bend tubes extend- ing through the tube sheet at the opposite end of said casing, and headers externally of said tube sheets and connecting the ends of tube legs of adjacent tubes supported by the same tube sheet. 65

7. A fluid heater comprising a casing, heat ab- 70 sorbing surface comprising horizontal rows of single return bend tubes, said tubes extending transversely of said gas pass and cantilever sup- ported from opposite sides thereof, each of said 75 tubes having a pair of oppositely inclined leg portions arranged in a plane between the planes of laterally adjacent return bend tubes supported from the opposite side of said gas pass, a liquid and vapor drum, downcomer tubes providing a

liquid supply from said drum to the lowermost tube legs, means connecting corresponding tubes in said rows supported at the same side of said gas pass for a serial fluid flow therethrough, and 5 riser tubes connecting the uppermost tube legs to said drum.

8. A fluid heater comprising a casing, heat absorbing surface comprising vertically spaced horizontal rows of single return bend tubes, said tubes 10 extending transversely of said gas pass from opposite sides thereof, said casing having a removable metallic tube sheet at each side of said gas pass, each of said tubes having leg portions extending through and expanded into the corresponding tube sheet and arranged between the leg portions of laterally adjacent return bend tubes extending through the tube sheet at the opposite side of said gas pass, headers positioned externally of each tube sheet and serially connecting adjacent leg portions of vertically adjacent tubes, a liquid and vapor drum, downcomer tubes providing a liquid supply from said drum to the lowermost tube legs, and riser tubes connecting the uppermost tube legs to said drum.

25 9. A heat exchanger comprising a casing, heat transfer surface comprising horizontal rows of return bend tubes, said tubes extending transversely of said casing from opposite ends thereof, each of said tubes having a return bend portion 30 extending transversely of the laterally adjacent leg portion of a tube supported at the opposite end of the casing, and means providing a supporting connection between the return bend portion of said tube and said laterally adjacent leg portion.

40 10. A heat exchanger comprising a casing, heat transfer surface comprising horizontal rows of return bend tubes, said tubes extending transversely of said casing from opposite ends thereof, each of said tubes having leg portions extending between the leg portions of adjacent return bend tubes extending from the opposite end of said casing, each of said tubes having a return bend portion adjacent to said opposite end of the 45 casing and extending transversely of the adjacent leg portions of vertically adjacent tubes in rows extending from the opposite end of the casing, and means providing a supporting connection between the return bend end of said tubes and 50 one of said laterally adjacent leg portions permitting relative expansion and contraction of said tubes.

55 11. A heat exchanger comprising a casing, heat transfer surface comprising horizontal rows of return bend tubes, said tubes extending transversely of said casing from opposite ends thereof, said casing having a removable metallic tube sheet at each end thereof, each of said tubes having leg portions extending through and expanded 60 into the corresponding tube sheet and arranged in a plane between the planes of laterally adjacent return bend tubes extending through the tube sheet at the opposite end of said casing, each of said tubes having its return bend portion adjacent to said opposite end of the casing and extending transversely of the adjacent leg portions of vertically adjacent tubes in rows supported at 65 said opposite end of the casing, and means providing a supporting connection between the return bend end of said tubes and one of said laterally adjacent leg portions permitting relative expansion and contraction of said tubes.

70 12. A heat exchanger comprising heat transfer surface including vertically spaced horizontal rows of single return bend tubes, a casing for said

75 surface including a tube supporting plate, each of said tubes having a pair of oppositely inclined leg portions extending through and expanded into said supporting plate to form a cantilever support for said tube, and headers arranged externally of said supporting plate for serially connecting and being supported on the projecting ends of adjacent leg portions of vertically adjacent tubes.

13. A heat exchanger comprising a casing, heat transfer surface comprising vertically spaced 10 horizontal rows of single return bend tubes, said tubes extending transversely of said casing from opposite ends thereof, said casing having a removable metallic tube sheet at each end thereof, each of said tubes having oppositely inclined leg 15 portions extending through and expanded into the corresponding tube sheet and arranged between and staggered relative to the leg portions of laterally adjacent return bend tubes extending through the tube sheet at the opposite end 20 of said casing, each of said tubes having its return bend portion adjacent to said opposite end of the casing and extending transversely of the adjacent leg portions of vertically adjacent tubes in rows supported at said opposite end of the casing, and means providing a supporting connection 25 for the return bend end of said tubes including a stud extending from each return bend portion and supported on one of said laterally adjacent leg portions.

30 14. A fluid heater comprising a casing, heat absorbing surface in said casing comprising vertically spaced horizontal rows of return bend tubes, said tubes extending transversely of said casing from opposite ends thereof, said casing having a removable metallic tube sheet at each 35 end thereof, each of said tubes having leg portions extending through and expanded into the corresponding tube sheet and arranged between the leg portions of laterally adjacent return bend tubes extending through the tube sheet at the opposite end of said casing, headers positioned externally of each tube sheet and serially connecting adjacent leg portions of vertically adjacent tubes, a liquid and vapor drum, downcomer tubes providing a liquid supply from said drum to the lowermost tube legs at each end of said casing, and riser tubes connecting the uppermost tube legs at each end of said casing to said drum.

40 15. A fluid heater comprising a casing having a gas inlet and a gas outlet at opposite sides thereof, a baffle arranged to divide said casing into a pair of upflow and downflow gas passes communicating at their lower ends with said gas inlet and outlet respectively, heat absorbing surface comprising horizontal rows of return bend tubes, said tubes extending transversely of each of said gas passes from opposite sides thereof, each of said tubes having leg portions arranged in a plane between the planes of laterally adjacent return bend tubes extending from the opposite side of said gas pass, each of said tubes having its return bend portion adjacent to one of said opposite sides of the gas pass and extending 45 transversely of the adjacent leg portions of vertically adjacent tubes in rows extending from the other of said opposite sides of the gas pass, and headers serially connecting adjacent leg portions of vertically adjacent tubes.

50 16. A fluid heater comprising a casing having a gas inlet and a gas outlet at opposite sides thereof, a baffle arranged to divide said casing into a pair of upflow and downflow gas passes communicating at their lower ends with said gas 55

5

- inlet and outlet respectively, heat absorbing surface comprising vertically spaced horizontal rows of single return bend tubes, said tubes extending transversely of each of said gas passes from opposite sides thereof, said casing having a removable metallic tube sheet at said opposite sides of said gas passes, each of said tubes having inclined leg portions extending through and expanded into the corresponding tube sheet and arranged between and staggered relative to the leg portions of laterally adjacent return bend tubes extending through the tube sheet at the opposite side of said gas pass, each of said tubes having its return bend portion adjacent to one of said opposite sides of the gas pass and extending transversely of the adjacent leg portions of vertically adjacent tubes in rows supported at the other of said opposite sides of the gas pass, headers positioned externally of each tube sheet and serially connecting adjacent leg portions of vertically adjacent tubes, a liquid and vapor drum, downcomer tubes providing a liquid supply from said drum to the lowermost tube legs, and riser tubes connecting the uppermost tube legs to said drum.
17. A heat exchanger comprising heat transfer surface including a plurality of return bend tubes, a casing for said surface including a tube supporting plate, each of said tubes having a pair of leg portions extending through and expanded into said supporting plate to form a cantilever support for said tube, and a header separate from and arranged externally of said supporting plate for serially connecting the projecting ends of leg portions of different tubes.
18. A heat exchanger comprising heat transfer surface including a plurality of single return bend tubes, a casing for said surface including a tube supporting plate, each of said tubes having a pair of oppositely inclined leg portions extending through and expanded into said supporting plate to form a cantilever support for said tube, and a header separate from and arranged externally of said supporting plate for serially connecting the projecting ends of adjacent leg portions of adjacent tubes.
19. A fluid heater comprising a casing having vertically spaced rows of return bend tubes, said tubes extending horizontally in said casing and being cantilever supported from opposite ends thereof, means connecting corresponding tubes in said rows supported at the same end of said cas-
- ing for a serial fluid flow therethrough, a liquid and vapor drum, conduit means providing a liquid supply from said drum to the lower ends of said serially connected tubes, and other conduit means connecting the upper ends of said serially connected tubes to said drum.
20. A fluid heater comprising a casing having a gas inlet and a gas outlet, baffle means forming a plurality of gas passes between said gas inlet and outlet, heat absorbing surface comprising vertically spaced rows of return bend tubes, said tubes extending horizontally in each of said gas passes and being cantilever supported from opposite sides thereof, each of said tubes having a return bend portion adjacent to one of said opposite sides of the corresponding gas pass and extending transversely of one of the leg portions of a tube supported at the other of said opposite sides of said gas pass, means connecting corresponding tubes in said rows supported at the same side of each gas pass for a serial fluid flow therethrough, a liquid and vapor drum, conduit means providing a separate liquid supply from said drum to the lower ends of the tubes supported at each side of said gas passes, and other conduit means connecting the upper ends of said tubes to said drum.
21. A heat exchanger comprising heat transfer surface including a plurality of return bend tubes, a casing for said surface including a tube supporting plate, each of said tubes having a pair of leg portions extending through and expanded into said supporting plate to form a cantilever support for said tube, and a header arranged externally of said supporting plate for serially connecting and being supported on the projecting ends of leg portions of different tubes.
22. A heat exchanger comprising a casing, heat transfer surface comprising horizontal rows of return bend tubes, said tubes extending in vertical planes transversely of said casing from opposite ends thereof, each of said tubes having leg portions extending between and staggered relative to the leg portions of adjacent return bend tubes extending from the opposite end of said casing, and each of said tubes having its return bend portion adjacent to said opposite end of the casing and extending transversely of and across the adjacent leg portions of vertically adjacent serially connected tubes in rows extending from the opposite end of the casing.

PERRY R. CASSIDY.
